UNITED STATES PATENT OFFICE.

FRANK W. FOSTER, OF MELROSE, MASSACHUSETTS.

ROUND SHAKING-GRATE.

SPECIFICATION forming part of Letters Patent No. 699,378, dated May 6, 1902.

Application filed December 2, 1901. Serial No. 84,357. (No model.)

To all whom it may concern:

Be it known that I, FRANK W. FOSTER, a citizen of the United States, and a resident of Melrose, in the county of Middlesex and State 5 of Massachusetts, have invented new and useful Improvements in Round Shaking-Grates, of which the following is a specification.

My invention relates to shaking-grates; and it consists of improvements in their structure whereby all the advantages peculiar to 10 shaking grate-bars and usually obtained in a square grate are secured in a round grate, such as is commonly placed under an upright tubular boiler.

15 In the drawings hereto annexed, which illustrate an embodiment of my invention, Figure 1 is a top plan view of a round boiler-grate whereon part of the grate-bars are removed and part broken away to exhibit the structure 20 of the lower portion. Fig. 2 is a top plan view of part of one of the grate-bars of the grate shown in Fig. 1 broken off near the middle thereof, as shown in the upper half of Fig. 1. Fig. 3 is a side elevation of the grate shown 25 in Fig. 1. Fig. 4 is a cross-section of the same grate; and Figs. 5 and 6 are views in plan and elevation, respectively, of one member of the ring-frame of the grate.

My improved round boiler-grate comprises 30 a frame with rocker-bars pivotally mounted thereon, which engage with movable grate-bars supported on the frame and circumferential extension-pieces which afford fire-supporting surfaces at the circumference of the 35 grate beyond the reach of the ends of the movable grate-bars. The grate-bars B, Fig. 1, are straight bars extending across the frame in such manner that each bar on one side of a diametrical division between the two middle 40 bars finds its duplicate on the other side.

The grate-bars, which occupy one-half of the circular space of the grate, diminish step by step in length and occupy as much of the entire surface of the grate as is practicable, 45 allowing for the longitudinal vibration of each bar. Around the circumference of the fire-supporting surface the spaces which in the nature of things cannot be occupied by movable grate-bars are filled with extension-pieces D, which, together with the movable 50 bars, are supported upon the grate-frame.

The frame of the grate is composed of segmental curved bars A and straight chord-bars A', which are bolted to the ends of the curved bars, brackets A³, and legs A⁴, Fig. 3. The 55 curved bars A in the construction herein shown are four in number, arranged in pairs, which are suitably bolted together, and are provided with depending hangers A⁵, Figs. 4 to 6, to which the chord-bars A' are bolted, the 60 chord-bars thus occupying a level lower than the curved bars A. Supports for the outermost movable grate-bars and the end extension-pieces which adjoin the said bars are provided in the shape of brackets A³, which are 65 bolted to and extend outward and upward from the chord-bars A'. Upon the upper edge of the curved bars A are notches A², which serve as supports and guides for the movable 70 grate-bars, and secured to or cast integral with the curved bars A and brackets A³ are the sockets D⁴, which provide for the circumferential extension-pieces D.

Rocker-bars C extend diametrically across the grate at right angles to the movable grate-bars and are pivotally supported at their ends upon the chord-bars A'. The rocker-bars C are duplicates and either one may serve in the place of the other merely by being turned end for end in the frame. Rocker-heads C' extend upward from the rocker-bars C and are so disposed thereon that the rocker-heads in one bar stand opposite to the spaces between the rocker-heads of the other bar. At C² the rocker-bars are joined to links C³, which 80 are articulately connected to the rocker-handles C⁴.

The grate-bars B are of skeleton form, provided with longitudinal webs B' and branches B² extending therefrom. At intervals opposite branches B² are joined together, so as to form the transverse webs or ties B³. The rocker-heads C' engage with the webs B' of the grate-bars. These webs on each grate-bar are suitably notched at a point a little at one 95 side of the middle of the bar, so that any grate-bar is susceptible of engagement with either rocker-bar by turning the grate-bar end for end. The circumferential extension-pieces D consist of open grills having fingers 100 D', which interlock with the end fingers B⁵ of the movable grate-bars. The extension-

pieces D are provided with suitable depending stems, which engage with the sockets D⁴. Segmental side pieces D³ fill the outermost circumferential space not provided for either by the movable grate-bars or the circumferential extension-pieces D.

In a boiler-grate such as the one herein illustrated there is invariably a stronger draft at the middle of the grate than at the circumferential portion, and in order to insure a uniform fire I have provided an arrangement by which the inequalities of draft are compensated for.

In Fig. 2, where half of one of the bars of my improved grate is shown in plan, it will be observed that the air-spaces B⁴ between the fire-supporting branches B' are smaller at the middle of the grate-bar than they are at its outer end.

I so proportion the grate-bar and its fire-supporting parts that the ratio between fire-supporting iron and air-space changes progressively from the middle to the circumference of the grate, this ratio being greater at the middle than at the circumference. Thus in Fig. 2, which represents part of one of the middle bars of my grate, a length occupied by five branches B², as at b, will be occupied by only three such branches at b' and by four branches half-way between b and b'. I carry out this gradation of effective air-space from the middle of the grate outward in all directions, and by this means compensate for the greater natural draft at the center of the grate and assist the stoker in keeping an even fire.

What I claim, and desire to secure by Letters Patent, is—

1. In a round boiler-grate, the combination with a ring-frame, of parallel grate-bars supported at the ends on the frame and at the middle by rocker-bars, the rocker-bars, the ring-frame comprising straight chord members, whereon the rocker-bars are pivoted, side brackets on the chord members, the outer 40 grate-bars resting on the said brackets.

2. In a round boiler-grate, the combination with a ring-frame comprising straight chord members and side brackets projecting from said chord members, parallel grate-bars supported at the ends in the frame and at the middle by rocker-bars, the outer grate-bars resting in the said side brackets, the rocker-bars, pivotally hung on the frame, and an annular fire-supporting surface made in sections, filling the space between the ends of the grate-bars and the fire-box wall, and supported by the ring-frame.

3. In a round boiler-grate, the combination of parallel grate-bars supported by a frame, 60 the frame, consisting of ring-segments, hangers depending from the ring-segments, chord-bars secured to the hangers at a level below that of the ring-segments, and rocker-bars hung on the chord-bars, and connected to the 65 grate-bars, substantially as described.

Signed by me at Boston, Massachusetts, this 25th day of November, 1901.

FRANK W. FOSTER.
